ATTORNEY

UNITED STATES PATENT OFFICE.

PHILIP F. LENHART, OF NEW YORK, N. Y.

DESIGN FOR A TILE.

SPECIFICATION forming part of Design No. 31,610, dated October 3, 1899.

Application filed September 8, 1899. Serial No. 729,880. Term of patent 7 years.

To all whom it may concern:

Be it known that I, PHILIP F. LENHART, a citizen of the United States, residing at the borough of Brooklyn, in the city of New York and State of New York, have invented and produced a new and original Design for a Tile, of which the following is a specification.

My present invention refers to a newly designed tile for the facing of walls, flooring, and for other purposes.

In the annexed drawings, portraying my design, Figure 1 is a perspective view. Fig. 2 is a side elevation.

In examining the shape of my design for a tile as delineated in the drawings it will be found that at one end is a square head or figure A, having plane side faces at right angles

to the flat surface of the figure, and at the other end a similar square figure or foot B of less size than the head A. The head A ²⁰ and foot B are connected by the narrow neck C. Between said neck C and head A are the bevel-faces a, and between the neck C and foot B are the bevel-faces b.

I claim—

The design for a tile, substantially as herein shown and described.

In testimony whereof I affix my signature in presence of two witnesses.

PHILIP F. LENHART.

Witnesses:

FRED E. TASKER,
JAMES F. DUHAMEL.
